UNITED STATES PATENT OFFICE.

WILLIAM FLATTERY, OF PHILADELPHIA, PENNSYLVANIA.

HAND-REST.

No. 890,132.

Specification of Letters Patent.

Patented June 9, 1908.

Application filed January 13, 1908. Serial No. 410,531.

To all whom it may concern:

Be it known that I, WILLIAM FLATTERY, a citizen of the United States, residing at Germantown, a suburb of Philadelphia, county 5 of Philadelphia, and State of Pennsylvania, have invented certain new and useful Improvements in Hand-Rests, of which the following is a specification.

This invention relates to hand rests for 10 penmen's use, the object being to provide a rest especially adapted to be used by free hand penmen, whereby the hand will be supported in such a manner that it can move easily over the writing surface, so as to avoid 15 cramping of the hand caused by continuous writing.

Another object of my invention is to provide a hand rest which is so shaped that it will fit snugly over the joint of the metacarpal 20 bone of the little finger, and the pisiform bone of the carpus or wrist, so as to protect the same, the hand rest being held in position by an elastic band, which extends around the wrist.

25 Another object of my invention is to provide a hand rest which is formed of aluminum, having a boss on its convex surface, in which is mounted an anti-friction ball adapted to travel on the writing surface.

30 These objects are obtained by the novel arrangement and construction of parts hereinafter fully described and shown in the accompanying drawings, in which:

Figure 1, is a perspective view of my improved hand rest, showing it applied to the hand, and, Fig. 2, is a section through the hand rest detached.

In the drawings A, indicates the oval concavo-convex body of my improved hand 40 rest, which is preferably formed of aluminum, having a concavity shaped to fit snugly over the joint of the metacarpal bone of the little finger, and the pisiform bone of the wrist.

45 The body is provided with oppositely disposed openings A', adjacent its edges, which are cut away as shown at A², in which are adapted to fit the hooks B, secured to the ends of the elastic band C, which extends 50 around the wrist, and holds the rest in position. It will be readily seen by detaching

one of the hooks, the rest can be readily removed.

A boss D, is formed on the convex surface of the rest to one side of its center, which is 55 provided with a central bore, extending through to the concavity of the rest, in which is adapted to be placed a ball bearing E, the edges of the bore on the face of the boss are contracted so as to prevent the ball from 60 dropping out, and after the ball has been placed therein, a rivet or suitable plug F, is placed in the ball from the inside of the rest, so as to lock the ball therein.

In use the rest is secured on the hand as 65 clearly shown in Fig. 1, and the hand is turned so as to allow the ball to engage the writing surface, which is the proper position for holding the hand in writing, and it will be seen as the hand is moved to form the 70 character in writing, the rest forms a support for the hand, and allows it to move freely.

From the foregoing description it will be seen that I have provided a hand rest which 75 is exceedingly simple and cheap in construction, and one which will prevent pen paralysis, as in free hand writing the hand is not supposed to touch the paper at all, the little finger and ring finger gliding over the 80 surface, and when the writer is compelled to write all day in this manner, the hand becomes cramped, so that it soon becomes impossible to write at all.

Having thus described my invention what 85 I claim as new and desire to secure by Letters Patent is:

1. A hand rest comprising a concavo-convex body, provided with oppositely disposed openings and grooves, a boss formed on the 90 convex surface of the body, an anti-friction ball mounted in said boss, and an elastic band provided with hooks, adapted to fit in the openings and grooves of the body for securing said body on the hand. 95

2. A hand rest comprising an oval concavo-convex body, provided with oppositely disposed openings, adjacent the side edges, a boss formed on the convex surface of the body to one side of the center, provided with 100 a bore extending through said body, an anti-friction ball arranged in said bore, a plug se-

cured in said bore from the inner side of said body for securing said ball in place, and an elastic band adapted to extend around the wrist, provided with hooks at its ends, adapted to fit in the openings of the body for securing said body over the joint of the hand.

In testimony whereof I have signed my name to this specification in the presence of two subscribing witnesses.

WILLIAM FLATTERY.
